UNITED STATES PATENT OFFICE.

HUGO MAUL, OF RAILWAY, NEW JERSEY.

DESIGN FOR TRIMMING-BRAID.

SPECIFICATION forming part of Design No. 29,208, dated August 9, 1898.

Application filed July 15, 1898. Serial No. 686,040. Term of patent 7 years.

To all whom it may concern:

Be it known that I, HUGO MAUL, of Rahway, in the county of Union and State of New Jersey, have invented and produced a new and original Design for a Trimming-Braid, of which the following is a full, clear, and exact specification.

Reference is to be had to the accompanying drawings, forming a part of this specification, in which similar characters of reference indicate corresponding parts in both the figures.

Figure 1 is a face view of a piece of braid, showing my design; and Fig. 2 is a sectional plan view of the same on the line 22 in Fig. 1.

The design consists of a body A, across the

spaced ribs B, interlocked at their ends in the borders C, appearing along the edges of the body A, the latter being corrugated transversely, the corrugations appearing at angles 20 to the ribs B.

The leading feature of my design consists of a body having spaced ribs appearing obliquely in the face thereof.

I claim—

The design for a trimming-braid, as herein shown and described.

HUGO MAUL.
